United States Patent Office.

ISAAC STRAUB, OF KENTON COUNTY, KENTUCKY.

Letters Patent No. 65,133, dated May 28, 1867.

IMPROVEMENT IN GRINDING-MILLS.

The Schedule referred to in these Letters Patent and making part of the same.

TO ALL WHOM IT MAY CONCERN:

Be it known that I, ISAAC STRAUB, of the county of Kenton, and State of Kentucky, have invented an "Improvement in Portable Grinding-Mills," and I do hereby declare the following to be an exact description thereof, reference being had to the accompanying drawings, and to the letters of reference, marked thereon, making a part of this specification, in which—

Figure 1 represents a perspective view of that class of portable grinding-mills that require the stones to be lifted out of the mill-frame when necessary to be dressed.

Figure 2 represents the tram-supports.

The nature of my invention consists in an additional tram-support, by means of which the millstone is perfectly re-set in its former position, and in tram with the runner after it had been removed and dressed.

The upper stone represents the bed-stone. Heretofore the difficulty in replacing the millstone has been to get it to its former and proper relative position with the runner, where four tram-supports have been used, at equi-distances apart. I therefore add, what I style a true register, a fifth tram-support, located between any two of the other supports, as seen at *b*, figs. 1 and 2. The ordinary tram-supports are lettered *a a a a*, and shown also at figs. 1 and 2, and by my odd tram-support *b* I always secure a perfect tram and correct position of the relative parts to fit precisely, as before the stone was removed. The bolt *b* is the same in construction as bolt *a*, which I do not claim, but—

What I claim as my invention, and desire to secure by Letters Patent, is—

The bolt *b*, when used in combination with tram-bolts *a a a a*, for the purposes substantially as described.

ISAAC STRAUB.
